METHOD FOR THE PRODUCTION OF COLOR
PRINTING PLATES

Walter F. Sinn, Ridgewood, Brooklyn, N. Y.

Application September 2, 1936, Serial No. 99,073

6 Claims. (Cl. 95—5.1)

The present invention relates to a method of making color printing plates for the production of multi-color printed pictures and designs from a black and white original or from a black and white or "neutral" negative made from a colored picture, the method obviating the use of a color camera and the preparation of a negative for each color.

5

The present method of preparing color printing plates involves the use of a separate negative for each coloration separation. The process requires considerable time, great care and skill and is very expensive for commercial use not only in the preparation of the negatives, but in finishing the color printing plates after the respective images have been produced thereon.

The characteristic of the present invention is that a single key negative is employed for each color separation in conjunction with masks which control the color shading and all desired modification of the original picture. The colors indicated for the specific picture may be brought out according to nature or to the requirements of the finished picture with exactitude, whereas, 25 in the preparation of a separate negative for each of a plurality of colors, by the use of a color camera, certain colors by reason of their light refractive properties are not correctly reproduced, and there is a tendency for an "overlapping" of 30 colors, so that in addition to the greater initial cost there is added the necessity for skilled and expensive work in correcting, changing and finishing the metal printing plates, with the final result uncertain. All of this is avoided by means 35 of the present invention.

The invention will be described with reference to the accompanying drawings, in which:—

Figure 1 is a plan view of a black and white picture designed for multicolor reproduction.

40 Figure 2 is a plan view of a key negative retouched to add highlights and brilliance to the several color positives later to be made therefrom.

Figure 3 is a plan view of the first exposure mask.

Figure 4 is a plan view of a positive plate produced by first exposure of the key negative in conjunction with the first mask illustrated in Figure 3.

50 Figure 5 is a schematic view showing the position of the key negative, mask and the sensitized plate in the production of the first exposure image shown in Figure 4.

Figure 6 is a schematic view showing the sensitized plate bearing the image of Figure 4

subjected to a second exposure through the second exposure mask shown in Figure 7.

Figure 7 is a plan view of the second exposure mask.

Figure 8 is a view of the sensitized plate in 5 its condition after the second exposure.

Figure 9 and Figure 10 are schematic views showing the use of the positive plate illustrated in Figure 8 for photogravure work, Figure 9 showing a first exposure upon carbon tissue 10 through a screen, and Figure 10 showing a second exposure upon carbon tissue bearing a screen image of the image illustrated in Figure 8.

Figure 11 is a diagrammatic view in perspective, showing the reproduction of the image illustrated in Figure 8 upon a photomechanical plate through a screen by photography.

Figure 12 is a plan view of the first exposure mask for a second color.

Figure 13 is a plan view of an image produced 20 photographically by exposure through the key negative of Figure 2, and the first exposure mask of Figure 12.

Figure 14 is a plan view of the second exposure mask, for said second color.

Figure 15 is a plan view of the image plate shown in Figure 13 after the second mask exposure.

Referring to the drawings, I have shown in Figure 1 a plan view of a black and white or "neutral" picture selected for reproduction in multi-color, and therefore through the production of a printing plate for each color. The first step in my process is to prepare the key negative 30 of the desired size from the original picture shown in Figure 1. Of course, if the original picture is smaller than that desired for the printing plate, the key negative will be an enlargement and vice versa. The key negative then is re- 35 touched by emphasizing the highlights through the application of opaque or semi-opaque coating upon the negative at those parts desired to be brought out in brilliance, as shown in Figure 2. I then prepare a mask which will be

opaque as to all of the areas not desired for the particular color. The mask is shown in Figure 3 and it will be noted that the original picture has been blocked out by an opaque material except for the two faces and the hand and that the face areas have been shaded, the shaded areas 40 partially shutting out the light so as to either block out the particular matter at the shaded areas or reduce its intensity according to the use of either an opaque sheet or a partially opaque sheet.

45

50

55

It will thus be seen that in the key negative all of the detail to be found in the original picture and in the multi-color reproduction thereof will appear. In the first exposure mask shown in Figure 3, the area of the original picture, not to be printed in the particular color for the mask as designed, will be made opaque as at 1x, Figure 3, with the exception that the opaque portion of the first exposure mask may also include areas 10 of the sensitized plate which are light exposed through the use of the second exposure mask, as later to be explained.

In the first exposure mask certain of the shaded highlights of the mask are indicated at 2.

15 After the preparation of the first exposure mask 1, it is placed in contact with the key negative 3 at the emulsion face thereof and the two placed in contact with a sensitized plate 4. Thereupon an exposure is made, as by use of a light source 5.

20 After the employment of the first exposure mask and key negative as described, I place the second exposure mask 6 upon the partially exposed sensitized plate of Figure 4, as schematically shown in Figure 6, and thereby intensify 25 those areas where deep color is desired, in the present example, the hair areas 6x, the color decorative band 7 and the shoulder decorative members 8, the final result being shown in Figure 8. This production of color intensity at the 30 areas stated cannot be satisfactorily produced in the first exposure through the key negative because of the density of the latter in exemplifying the complete design, but the second exposure of the sensitized plate satisfactorily brings out the 35 desired effect without modifying the highlight areas, these areas being protected by the opaque portion 6xx of the second exposure mask.

It will be understood that a very simple picture has been selected to illustrate the successive 40 steps of my method and that the process is applicable to all types of picture and design reproductions whether they incorporate intricate detail or simple forms.

The completed positive produced by my method 45 is shown in Figure 8, that part of the original picture to be printed in yellow, as an example, having been reproduced. The yellow will be intensified at the hair areas 6x and the costume elements 7 and 8.

50 In the production of the mechanical printing plate, I have indicated in Figure 9 a sheet of carbon tissue 9, a screen 10 and a light source 11. The first step is to print the screen upon the carbon tissue by a first exposure and, as indicated in Figure 10, to print the image through the positive plate of Figure 8 upon the carbon tissue bearing the screen image. The finished positive, for the color yellow is indicated in Figure 10 at 55 12. The carbon tissue may then be employed in the usual photo-gravure processes for the production of the final ink receiving printing plate.

60 For the production of a half-tone ink receiving printing plate, the positive 12 may be placed upon an easel 13 and light thrown upon it from the rear as by the carbon arcs 14, a rear light reflector 15 preferably being employed. Within a camera 16 will be placed the half-tone screen 65 17 and back of the screen a sensitized plate 18. The positive 12 may by means of the camera be 70 suitably enlarged or reduced. From the final plate 18 may be printed and etched the final ink receiving printing plate as will be understood without further explanation.

To further illustrate the invention, I have shown in Figures 12 to 15 inclusive, the prepara-

tion of a positive for a second color, selecting red as an example, inasmuch as for the subject illustrated the color red is suitable throughout the composition. In Figure 12, I have indicated at 19 the first exposure mask for the color red. As in the production of the positive plate for the first color, yellow, mask 19 is placed in contact with the key negative 3 and through the mask and negative light is projected onto the sensitized plate, the first exposure resulting in the image 10 shown in Figure 13 at 20. In the mask 19 certain highlights, as, for example, the eyes, the teeth area of the woman figure, color and white exposed shirting of the male figure, etc. are made opaque or suitably shaded so as to entirely 15 eliminate color or reduce color at such points. After exposure of the positive plate through the first exposure negative, for the color red, a second mask indicated in Figure 14 at 21 is employed. The purpose of the latter mask is to intensify 20 the color red at certain areas without affecting the general design and shading at remaining areas. Thus the cheeks are intensified by the lightly shaded areas 21x. At the area 22x the color red is intensified largely for the purpose of 25 color blending with a subsequent color, blue, for example, the area being shaded however in the present example to aid in the draping effect of the woman's garment.

Referring back to Figures 12 and 13, it will be 30 seen that in the background 19x light has been held back to a certain degree so that in the first exposure of the sensitized plate through mask 19 the background will be substantially lighter than the figures and hence carry substantially 35 less of the color red.

By reason of the use of the second mask 21, in the final positive 22, the dress of the woman's figure will be predominantly red, fresh tone with 40 high color at the cheeks of the woman will be produced by the combination of red and yellow at such areas, the highlights of the hair will appear with the yellow or gold coloration of the costume elements 8 emphasized and each detail of the figures including their costumes brought 45 out with exactitude as to color and detail.

Where a group of two or more pictures is laid out for a single print, as frequently in color advertising, I use but one negative for the entire group, whereas by present methods, three separate negatives are required for each picture of the group in order to secure the required colors. For example, a group of six pictures to be used in one advertisement, will require at least eighteen negatives. My process can accomplish the 55 result with a single negative.

My process does away with all the skilled and expensive work now required in correcting, changing and finishing metal color printing plates. This work of preparing the printing plates often requires weeks of time and is very expensive. In my process, all corrections are readily made on the original negative and by the use of hand made masks in preparation of color separation positives. This requires comparatively short time and small expense.

I claim my process can be used to advantage in the reproduction in print of colored pictures as above outlined, in photo-engraving, photolithography, photo-gravure, rotogravure and 70 photo-offset work. All production in these lines by present methods is expensive, as, for example, requiring the services of skilled finishing engravers, whereas in my process the design is controlled by the original negative and the color is

controlled by the masks in preparing the color separation positives. My process also permits of simple, easy registration of color plates during the process, as the prints are made from original negative and color separation plates for registration and correction instead of metal printing plates as required in present processes.

Having described my invention, what I claim and desire to secure by Letters Patent, is as follows:

- 10 1. In the production of color printing plates, the step of producing a transparent key negative of the desired image, the step of reproducing the image through said negative upon a sensitized photographic surface whilst blocking out areas of the image not to be reproduced in the given color, the step of subjecting the sensitized surface to a second exposure through a mask which passes light rays to those areas of the image on the sensitized surface desired to be shown in a relatively deep color density, developing the positive thus produced, and photographically reproducing the position upon a photo-mechanical plate.
- 15 2. In the production of first and second color printing plates, the step of producing a transparent key negative of the desired image, the step of reproducing that part of the image selected for the first color by light exposure upon a sensitized surface through said negative and a mask which blocks out areas of the image not to be reproduced in said color, as a step in the process subjecting the sensitized surface to an exposure through a second mask which passes light rays to those image areas desired to be shown in relatively deep color density, the step of light exposing a second sensitized surface through said negative whilst blocking out areas of the image not to be reproduced in the second color, subjecting the second sensitized surface to an exposure through a mask which passes light rays to those image areas desired to be shown in relatively deep color density, developing the positives thus produced, and photographically reproducing each positive upon a photo-mechanical medium.
- 20 3. In the production of first and second color printing plates, the step of producing a transparent key negative of the desired image, the step of reproducing that part of the image selected for the first color by light exposure upon a sensitized surface through said negative and a mask which blocks out areas of the image not to be reproduced in the second color, subjecting the second sensitized surface to an exposure through a second mask which passes light rays to those image areas desired to be shown in relatively deep color density, the step of light exposing a second sensitized surface through said negative whilst blocking out areas of the image not to be reproduced in the second color, subjecting the second sensitized surface to an exposure through a mask which passes light rays to those image areas desired to be shown in relatively deep color density, developing the positives thus produced, and photographically reproducing each positive upon a photo-mechanical medium.
- 25 4. In the production of first and second color printing plates, the step of producing a transparent key negative of the desired image, the step of coloring said negative to add highlights and brilliance, the step of reproducing that part of the image selected for the first color by light exposure upon a sensitized surface through said negative and a mask which blocks out areas of the image not to be reproduced in said color, as a step in the process subjecting the sensitized surface to an exposure through a second mask which passes light rays to those image areas desired to be shown in relatively deep color density, the step of light exposing a second sensitized surface through said negative whilst blocking out areas of the image not to be reproduced in the second color, subjecting the second sensitized surface to an exposure through a mask which passes light rays to those image areas desired to be shown in relatively deep color density, developing the positives thus produced, and photographically reproducing each positive upon a photo-mechanical medium.
- 30 5. In the production of first and second color printing plates, the step of producing a transparent key negative of the desired image, the step of coloring said negative to add highlights and brilliance, the step of reproducing that part of the image selected for the first color by light exposure upon a sensitized surface through said negative and a mask which blocks out areas of the image not to be reproduced in said color, as a step in the process subjecting the sensitized surface to an exposure through a second mask which passes light rays to those image areas desired to be shown in relatively deep color density, the step of light exposing a second sensitized surface through said negative whilst blocking out areas of the image not to be reproduced in the second color, subjecting the second sensitized surface to an exposure through a mask which passes light rays to those image areas desired to be shown in relatively deep color density, developing the positives thus produced, and photographically reproducing each positive upon a photo-mechanical medium.
- 35 6. In the production of first and second color printing plates, the step of producing a transparent key negative of the desired image, the step of coloring said negative to add highlights and brilliance, the step of reproducing that part of the image selected for the first color by light exposure upon a sensitized surface through said negative and a mask which blocks out areas of the image not to be reproduced in said color, as a step in the process subjecting the sensitized surface to an exposure through a second mask which passes light rays to those image areas desired to be shown in relatively deep color density, the step of light exposing a second sensitized surface through said negative whilst blocking out areas of the image not to be reproduced in the second color, subjecting the second sensitized surface to an exposure through a mask which passes light rays to those image areas desired to be shown in relatively deep color density, developing the positives thus produced, and photographically reproducing each positive upon a photo-mechanical medium.

WALTER F. SINN.
